Primary Examiner—Stella Reid
Attorney, Agent, or Firm—Richard P. Crowley[57] **CLAIM**

The ornamental design for a pocket-size sanitation test kit, as shown and described.

DESCRIPTION

FIG. 1 is a side elevational view of a pocket-size sanitation test kit, showing our new design, the other side elevational view being a mirror image;

FIG. 2 is a front elevational view thereof of FIG. 1;

FIG. 3 is a rear elevational view thereof of FIG. 1;

FIG. 4 is a top plan view thereof of FIG. 1;

FIG. 5 is a bottom plan view thereof of FIG. 1;

FIG. 6 is a rear elevational view thereof of FIG. 1, with the top portion detached;

FIG. 7 is a side elevational view thereof of FIG. 1, with the top portion fully inserted into the bottom portion; and,

FIG. 8 is a side elevational view thereof of FIG. 1, after use, with the bottom tube portion detached.
